WINDOW CONSTRUCTION

Edmund Peremi, Manhasset, and Louis Toth,
Flushing, N. Y.

Application November 2, 1938, Serial No. 238,351

6 Claims. (Cl. 189—72)

This invention relates to metal windows. One object of the invention is to provide an improved metal window frame construction which may be made of comparatively light metal and built into a masonry wall during the progress of the construction of the wall, the masonry being built directly into the metal frame so as to reinforce the same. This permits the use of lighter metal than would otherwise be the case. The invention also contemplates the provision of means associated with the frame for bonding the same into the masonry.

Another object of the invention relates to the provision of a frame construction of very simple configuration which can be made out of rolled sheet metal, preferably non-ferrous or non-corrosive metal, such as aluminum, bronze or stainless steel.

Another object of the invention comprises the provision of a frame construction which may be erected in multiple units, so that any desired number of window units may be readily assembled in a single elongated window opening.

Another object of the invention is the provision of improved weather stripping means for double-hung windows in which a single weather stripping unit is utilized for both sashes.

Other objects and advantages of the invention will appear in connection with the following description of certain preferred embodiments of the invention chosen to illustrate the principles thereof.

In the accompanying drawings,

Figure 1 is a front elevation of a portion of a wall having two double-hung window units mounted in a single window opening therein;

Figure 2 is a vertical section on line 2—2 of Fig. 1;

Figure 3 is a horizontal section on line 3—3 of Figure 1;

Figure 4 is a vertical section on line 4—4 of Fig. 3;

Figure 5 is a vertical section on line 5—5 of Fig. 3 showing the sash stile and a part of the window jamb and one of the spring anti-rattling members;

Figure 6 is a view similar to Fig. 5 showing a modification of the anti-rattling member;

Figure 7 is a perspective view of the anti-rattling member shown in Fig. 6;

Figure 8 is a vertical section through a double-hung window showing a modification of the construction shown in Figs. 1, 2 and 3; and

Figure 9 is a horizontal section on line 9—9 of Fig. 8.

Referring to the drawings in detail, and particularly to Figs. 1 to 5, the window frame shown is composed of a header 20, a sill 21, two side jambs 22 and a mullion 23. All of these parts are of such shape that they may be formed from rolled sheet metal, preferably of a non-ferrous or non-corrosive metal, such as aluminum, bronze or stainless steel.

Referring particularly to Fig. 3, it will be seen that the window jamb comprises a channel member having an outside wall 30 which preferably terminates at its outer edge or edge furthest from the window opening in an outwardly directed lip 31 which is set within the masonry, the space 10 between the wall 30 and the lip 31 forming a pocket for caulking 33. The wall 30 forms the outer stop bead for the window, and is bent upon itself at its inner edge to form an overhanging lip 35 and then is doubled back, as shown at 36, and then is bent transversely to form the web or back 38 of the channel. At the edge of the web 38 nearest to the inside of the building, the metal is bent to form a flange 40 which preferably terminates in a lip 41. Centrally of the back or web 15 38 an off-set or rabbet 42 is preferably formed to provide a seat for a parting strip 44, which is removably secured in place in any suitable manner, as by screws 45. The web or back is also preferably formed to provide a rabbet 48 in which seats the inner stop bead 50 which has a flange 51 terminating in a lip 52. The stop bead 50 is 20 preferably removably retained in position in any suitable manner, as by means of screws 53. When the window frame is to be used, it is set in position and the wall built alongside of it, the masonry, especially the mortar or concrete, being filled into the channel formed by the side wall 30, the channel back or web 38 and flange 40. The channel is thus filled solidly with the masonry 25 which reinforces the frame and enables it to hold its shape, although it may be made of relatively light metal. At the same time the masonry is bonded to the frame by means of bonding plates 55. These may be flanged as shown at 56 for attachment to the jamb channel by welding or 30 in any other suitable manner, and are preferably provided with corrugations 57 or the like.

The mullion shown in Figure 3 is preferably formed out of a single piece of sheet metal bent 35 to provide two webs 60, each of which has an off-set 61 for receiving the parting strip 44, and each web being offset to provide a rabbet 62 near its inner edge for engagement with a channel member 65 carrying inner stop beads 66 preferably terminating in lips 67. The channel mem-

ber 65 is removably held in position in any suitable manner as by means of screws 68. At the outer side of the mullion the webs 60 are bent upon themselves to form outer stop beads 75 preferably provided with lips 76. The mullion construction shown will thus be seen to be comprised entirely of two bent sheet metal channel-shaped members interlocked and secured together. A very light, cheap and strong construction presenting a finished appearance from both inside and outside, is thus provided.

The upper and lower window sashes 80 and 81 are shown as formed of extruded hollow metal sections, a construction which we prefer, although any other suitable sash construction may be employed. The sashes are preferably arranged to slide in contact with opposite faces of the parting strips 44 and in order to hold them in contact with such faces and to assist in making a tight seal against the weather and to prevent rattling, the sashes are each provided with resilient devices adapted to slide along the inside of the stop bead and to hold the other face of the sash against the parting strip.

In Figures 4 to 7 we illustrate preferred examples of such yielding devices which as shown are in the nature of an improvement on the yielding device shown in U. S. Patent No. 1,808,608, dated June 2, 1931.

In Figures 4, 5, and 6 the yielding members are shown as arched spring wires 90 having bent ends 91 and 91a adapted to pass through holes 92 and 93 respectively in the side wall of a sash stile, the hole 93, being in the form of an elongated slot so as to permit yielding movement of the bent wire. The end 91a of the wire 90 may preferably be provided with threaded eyelet 98, and the hollow rail may have the small screw 99 inserted therethrough to engage the eyelet 98. It will be seen that the tension exerted by the yielding members may be adjustably varied by turning of the screw.

Figure 7 shows a modified form of yielding member in which the spring wire 95 is provided with a shoe 96 preferably formed of a U-shaped piece of metal into which the wire is inserted, the walls of the U being then clamped together as indicated at 97 so as to fix the shoe permanently to the wire. The shoe provides an enlarged bearing surface against the inside of the stop bead and permits the use of the kind of metal best adapted to slide smoothly, and without wear on the metal of which the stop beads are formed. It is thus possible to use a metal for the shoe which might be too soft or of unsuitable character to form the spring portion 95.

For further retaining the window weather tight and for guiding it against movement laterally in the plane of the window, while at the same time permitting a free raising and lowering movement at all times without sticking or binding, we provide weather stripping or sealing means having resilient tongues 100 made of resilient, non-corrosive sheet metal and adapted to bear against the edges of the sash stiles. The outer edges 101 of the weather stripping members are preferably of a single-thickness of metal without reinforcement, and may, therefore, be referred to as "raw" edges. This gives the weather stripping members great flexibility in a longitudinal direction and enables them to conform to the sashes at all times, so as to secure the best possible seal against the weather. The overhanging lips 35, 52, 67 and 76, respectively,

serve to guard and protect the edges of the tongues and also to limit the outward movement of the tongues when the sash is not in place, thereby permitting the resilient tongues to be so set as to be held under an initial tension. For cheapness of manufacture and ease of assembly, the tongues 100 are preferably part of a single sheet of metal, the central part of which between the tongues constitutes a shouldered piece 103 which is adapted to fit in the off-set or rabbet 42 formed in the web of the frame member, and held in such position by the parting strip 44 and its retaining screws 45.

The great simplicity of the construction shown is now apparent. Considering the jamb shown at the left hand side of Figure 3, it will be seen that this consists of the following four members plus a few attaching screws, namely, the flanged channel member, the inner stop bead, the parting strip and the double tongued weather strip. The mullion consists entirely of six members, namely, the member comprising the two webs 60 and the end wall 75, the channeled member 65 which includes the two stop beads, two parting strips and two double tongued weather strips.

Referring to Fig. 2, the header 20 of the window frame is shown as comprising a sheet metal channel member which is preferably of the same cross section as the jamb channel member 22. As only one of the sashes is required to make a sealing engagement with the header, a weather strip is used which is provided with a single flexible tongue 100 mounted in any suitable manner, as by being formed on a base 103a adapted to be held in a central rabbet in the header member by the parting strip 44. Instead of using a flanged inner stop bead member, a flat plate 110 may be mounted in the rabbet 62 and serves to cover the edge of the plaster 111.

The window sill 21 is shown as formed of a single piece of sheet metal bent to provide a step 120 adapted to engage a resilient weather strip 121 in the bottom rail of the sash, the sill also having an inner step 125 which is contacted by the inner face of the sash. At the inner edge of the sill the metal is preferably doubled to form a lip 126 adapted to align with the inner stop beads and the inner edge of the plate 110. The hollow sill is preferably filled with concrete 128 to give it strength and rigidity and prevent it from being accidentally dented.

Referring to Figures 8 and 9, these show a modification of the window frame construction shown in Figures 2 and 3. The jamb shown in cross section in Figure 9 comprises a member 130 of extruded metal such as aluminum or bronze, which is provided with an outer flange 131 forming an outer stop bead and with a narrow flange 132 forming an extension of the flange 131. At its inner edge the member 130 is rabbed and holds an inner stop bead 51 preferably formed of an extruded section. The member 130 is shown as mounted upon a sheet metal backing member 140 which is provided at its outer edge with a flange 141 terminating in a lip 142, the flange and lip forming a weather stop and being preferably embedded between the masonry 143 and caulking material 144. The backing member 140 is shown as continued inwardly to the inside line 150 of the plaster wall of the room, the portion 151 of the backing member forming a metal reveal for the window opening. At its inner edge the member 140 is bent upon itself to form a corner bead 152 and is then extended in the form of a flange having

an angular portion 153 and a flat portion 154. These portions key into the plaster so that a strong and finished corner is provided between the metal reveal and the plaster wall. The corrugated tie plates 55 may be secured to the back 5 of the jamb and the space back of the jamb and around the tie plates is preferably filled with masonry, as in the form of the invention shown in the previous figures.

The window header shown in Figure 8 is constructed similarly to the jamb member described, except that the flange 141a, at the outer edge of the backing member, is preferably made wide to give added strength and to provide a recess for the counterbalance spring boxes 160. The header member 400 is similar in cross section to the jamb 130 and includes a recess 401 in which is mounted a stop bead comprising a base 402 and a top rail engaging member 403 which is in alignment with the outer face of the parting strip 44 and engages in snug relationship with the top rail of the upper sash when that sash is in closed position.

The sill shown in Figure 8 comprises a bent or extruded non-ferrous or non-corrosive metal member 170 having an inclined apron portion terminating at its outer edge in a downwardly turned flange 171 and provided with steps 172 and 173 for engagement with the bottom rail of the sash. An angle piece 175 may also be secured on the member 170, the inner face of the vertical leg of the angle aligning with the edge of the parting strip 44 and engaging with the outer face of the bottom rail of the lower sash when the window is closed so as to form a water breaker and assist in sealing the bottom of the window. The sill member 170 is shown as mounted upon a sheet metal subsill 180 which is bent at its forward edge to form a double flange 181 reinforcing the corner of the outer sill member 170, the metal of the subsill being then bent downwardly to form a flange 182 adapted to cooperate with the flange 171 and the masonry to form a pocket for caulking 183. The subsill member is also formed with a shoulder 185 fitting under the shoulder 173 of the sill member. The subsill member is preferably continued inwardly to form a portion 186 corresponding with the reveals 151, this portion terminating in a bead 152 and flange portions 153 and 154, as already described in connection with the jamb. A window recess within the room is thus provided which is entirely lined with metal, the metal also providing corner beads for protecting the surrounding plaster.

The mullion construction shown in Figure 9 is formed of extruded metal parts and comprises two members 130 identical with the jamb members 130 already described. These members are held together by an outer channel or filler 190, the back of which rests against the inner flanges 132, the legs of the channel having offset portions 192 which interlock against offset portions 193 formed in the members 130. At the inner side of the mullion the members 130 are held together by a channel member or filler 200 which has inner flanges 201 projecting inside of the inner edges of the members 130, the channel 200 also being preferably provided with lips 202 adapted to rest against the inner edges of the members 130. The parts of the mullion are secured together in any suitable manner, as by screws 205. As the members 130 forming the mullion are identical with the side jamb members 130, it will be seen that a window frame 75

is provided which can be used either as a single unit with the members 130 on each side constituting jamb members, or any number of units may be assembled side by side with all of the members 130, except the two outermost members, constituting the side members of the mullions, adjacent members 130 being connected together by the filler channels 190 and 200. This permits great flexibility in the use of the window and various numbers of units may be assembled at the job to fill window openings of various size sashes as the architectural requirements of the building may determine.

While we have illustrated and described in detail certain preferred forms of our invention, it is to be understood that changes may be made therein and the invention embodied in other structures. We do not, therefore, desire to limit ourselves to the specific construction illustrated, but intend to cover our invention broadly in whatever form its principle may be utilized.

We claim:

1. In a metal window, a four piece jamb comprising a channel member, a parting strip in said channel member, a single resilient metallic weather strip member held by said parting strip in said channel member and having single ply flexible tongues extending in like configuration but in opposite direction from said parting strip, said channel member terminating at its outside edge in an integral flange constituting an outer stop bead and a flange constituting an inner stop bead removably secured to the inner edge of said channel member, said flange having a lip turned toward said parting strip, said lip adapted to overhang the free edge of the inner one of said flexible tongues, access being provided to said jamb and said weather strip by removal of said inner stop bead.

2. In a window jamb, a channel member, a parting strip and a weather strip, said channel member comprising an outer stop bead, formed by doubling the channel member at the outer edge thereof and inturning said double portion to form the bead, the outer portion of said bead extending laterally of the window and being flanged near its edge toward the outside of the window to provide a caulking pocket, said channel member having an inwardly extending web formed to provide a back for said jamb, said back having a recess therein adapted to receive said weather strip and said parting strip, said channel member further having an inwardly extending rabbet, and terminating at its inner edge in an outwardly extending flange, an inner stop bead fitting said rabbet, said inner stop bead being inwardly flanged and terminating in a lip turned toward said outer stop bead.

3. In a multiple unit double hung window, a mullion having a base parallel to the plane of the window and two inwardly extending webs, said webs having formed therein oppositely disposed recesses adapted to receive parting strips, said webs being offset toward each other near the inner edges thereof, and a channel shaped member having a base and two flanges, said flanges engaging and lying along said offsets on said inwardly extending webs then extending toward each window opening and terminating in outwardly turned lips.

4. In a window construction including a frame, a sill, and a subsill, said subsill having an inner corner bead and a flange extending downwardly therefrom, a shoulder situated outwardly from said corner bead, a downwardly outwardly slop-

ing portion terminating in a fold, and a flange extending downwardly from said fold, and said sill being provided with steps, one of said steps engaging said shoulder of said subsill, said sill also having an outwardly downwardly extending portion terminating in a downwardly extending flange which forms with the flange of said folded portion of said subsill, a caulking pocket.

5. In a sliding window, a sash and a frame including a sill having an outwardly downwardly extending apron with an angle support member mounted thereon, one leg of which engages the face of said apron and the other leg of which extends upwardly and engages snugly with the outer face of the sash when the sash is in closed position.

6. In a window construction, a mullion comprising two jamb members placed back to back, said members being divided from each other by two generally U-shaped members secured adjacent either edge of said jamb members, said jamb members being provided at their outer edges with flanges extending away from the window openings and adapted to overlie the base of outer U-shaped member and said jamb members terminating at their inner edges in portions substantially perpendicular to the plane of the window, the legs of said inner U-shaped member being attached to said portions.
